UNITED STATES PATENT OFFICE

2,457,572

WASHING MACHINE

Joseph B. Leonard, Detroit, Mich.

Application November 23, 1944, Serial No. 564,776

2 Claims. (Cl. 15—76)

1

This invention relates to a washing machine and more particularly to a washing machine for hollow or tubular members such as water glasses.

An object of the invention is to provide a rotatable brush, driven by a fluid pressure, which is automatically controlled by the application of the article to be washed on the brush.

Another object of the invention is to provide a plurality of adjacent brushes, rotatable in opposite directions, for cleaning the external and internal surfaces of an article such as a water glass.

A further object of the invention is to provide a motor, driven by a cleaning fluid under pressure, for rotatably driving a plurality of brushes and to control the flow of fluid through the motor, by a valve means operable by engagement of the article to be cleaned on one of the brushes.

Other objects and advantages of the invention will more fully appear from the following description taken in connection with the accompanying drawings in which—

Fig. 1 is a sectional view of my improved device showing an embodiment of my invention; and

Fig. 2 is a sectional view taken on line 2—2 of Fig. 1 on enlarged scale.

Referring to the drawings I have shown a motor housing 10 having a rotor chamber 12. The chamber 12 is elliptical and receives a rotor 14 having a diameter substantially square to the dimension of the minor axis of the elliptical chamber 12. A cover plate 16 is provided to close the open side of the chamber 12 and to position the rotor 14 in the chamber 12. The opposite faces of the rotor are in sliding engagement with a raised boss 18 on the bottom wall of the chamber 12 and an inwardly projecting boss 20 on the cover 16. The bosses 18 and 20 are elliptical as shown by dotted lines in Fig. 2 and the major axes thereof are of less dimension than the diameter of the rotor 14. There is provided between the wall of the chamber 12 and the bosses 18 and 20 an elliptical track or groove which receives a plurality of blades 22. The blades 22 are received in radially extending slots 24 which are spaced circumferentially in the rotor 14.

A tubular member 26 is journaled in the cover 16 and the bottom of the housing 10 and is fixed to the rotor 14 so that rotation of the rotor 14 causes rotation of the tubular member 26. The outer end of the tubular member 26 detachably receives a stem 28 of a brush 30. The stem 28 is provided with a longitudinal passage 32 having a valve seat 34 at its lower end. A valve rod 36 is

2

guided in the passage 32 and projects outwardly above the brush 30. A spring 38 abutting an apertured shoulder 40 in the passage 32 and the outer end of the rod, urges the rod 36 outwardly and normally closes the passage 32 from the tube 26 by a valve 42 on the rod 36 seating against the valve seat 34.

Below the valve 42, and carried by the rod 36, is a sleeve valve 44 normally closing lateral openings 46 in the tube 26. The sleeve valve 44 is provided with an opening 48 for the passage of the cleaning fluid therethrough.

Cleaning fluid under pressure is admitted to the motor through an inlet pipe 50 and branched passages 52 and 54. The fluid pressure at opposite sides of the rotor 14 causes rotation thereof in a direction indicated by the arrows in Fig. 2. Exhaust fluid is received in outlet passages 56 which are connected to the bottom of the tube 26 by passages 58.

When the parts are in the position as shown on the drawing the fluid passage 46 is closed thereby preventing a flow of fluid through the pump and consequently the rotor 14 is stationary.

25 When the valves 42 and 44 are opened such as by pressing the rod 36 inwardly, the discharge passage 46 is opened permitting the fluid to flow through the system and rotate the brush 30 driven by the rotor 14 and tube 26. Ordinarily 30 the rod 36 is operated by the application of a water glass over the brush 30, the bottom of the glass engaging the outer end of the rod 36 and a slight pressure downwardly permits the fluid to discharge into the housing 60. A portion of 35 the fluid is conducted through the passage 32 and discharged at the top of the brush 30, inside the glass draining over the brush 30 into the housing 60.

The housing 60 is detachably secured to the 40 motor housing 10 by screws 62 with a gasket 64 between the housing 10 and the housing 60. An overflow pipe 66 has been provided for discharging the fluid from the housing 60 and is of a predetermined height to maintain a constant 45 fluid level within the housing 60.

The tube 26 carries a gear 68 which meshes with gears 70 and 72 at opposite sides of the gear 68. The gears 70 and 72 are drivingly connected to 50 brushes 74 and 76 respectively. Rotation of the brushes are in opposite direction to the direction of rotation of the brush 30. The brushes 74 and 76 clean the outer periphery of the water glass when the latter is placed over the brush 30. The brushes 74 and 76 are journaled in an overhanging 55 projection 78 of the cover plate 16 and a re-

movable plate 80 which is secured to the projection 78 by screws 82. A spacer 84 positions the removable plate 80.

If it is desired to add a solvent or soap solution to the cleaning fluid, a container 86 may be secured to the side of the housing 60. A conduit 88 forms a passage for the solution from the container 86 to the fluid pipe 50. A valve 90 is shown in the passage for regulating the amount of solution admitted to the fluid pressure.

It will be understood that various changes including the size, shape and arrangement of parts may be made without departing from the spirit of my invention and it is not my intention to limit its scope other than by the terms of the appended claims.

I claim:

1. A washing device comprising a fluid motor having inlet and outlet passages, a tubular member journaled in said motor, said motor having a rotor carried by said tubular member, said motor outlet passage communicating with one end of said tubular member at one side of said rotor, said tubular member having an outlet passage at the opposite side of said rotor, a rotatable brush carried by said tubular member, a valve for the outlet passage in said tubular member, said brush having an axially extending passage therethrough, a valve for said axially extending passage, a rod extending through said axially extending passage projecting beyond said brush and carrying said valves, and rotatable brushes adjacent said first named brush and rotatably driven by said rotor.

2. A washing device comprising a fluid motor housing having inlet and outlet passages, a tubular member journaled in said motor housing, a rotor mounted in said housing and carried by said tubular member, said tubular member projecting outwardly beyond said housing, a gear mounted on said tubular member external of said housing, a pair of gears rotatably mounted on said housing and in driving engagement with said first named gear, the outer end of said tubular member having radially extending openings through its side wall, a valve for controlling the openings in said tubular member, a second tubular member forming an extension of said first tubular member and communicating therewith, a valve for controlling the communication between said tubular members, said valves being connected together, an axially extending rod projecting through the outer end of said second tubular member for moving said valves, and brushes rotatably driven by said gears.
